UNITED STATES PATENT OFFICE

JOHN LARSON, OF PHILADELPHIA, PENNSYLVANIA

MUSICAL TOY

Application filed November 28, 1931. Serial No. 577,807.

This invention relates generally to musical toys, and more particularly to grotesque reproductions of birds in which the movements of the beak and tail of the bird are imitated and a musical note is produced simultaneously with such movements.

The main object of the invention is to provide a toy of this character designed for production in large quantities and for sale 10 at low prices, and which will prove highly amusing to small children.

Other objects of the invention will become apparent as the detailed description thereof proceeds.

15 In the drawings:

Figure 1 is a perspective view of the complete toy;

Figure 2 is a central longitudinal section through the toy bird;

20 Figure 3 is a fragmentary section, similar to Figure 2 but showing the several parts in different positions; and

Figure 4 is a fragmentary perspective view of the operating mechanism of the toy.

25 As shown in the drawings, the toy comprises a cylindrical body 1 provided with a large central bore 2 in which the operating mechanism is concealed. The bore 2 is coaxial with a smaller bore 3 in which an extension 4 of a cylindrical member 5 is snugly fitted. A shoulder 6 at the junction of the extension 4 and member 5 contacts with the bottom wall 7 of bore 2 to limit the movement of member 5 in bore 2.

30 A bore 8 extends axially through the member 5 and extension 4; and a tapered bore 9 extends radially through the member 5 to receive a tapered hollow plug 10. The body 1 is provided with a radial bore 11 adapted

40 to register with the bore 9 and to receive and support the main body of the plug 10. It will be apparent from the drawings that when the plug 10 is inserted in the registered bores 9 and 11 the member 5 will be locked against 45 movement in any direction in the large bore 2.

The plug 10 is axially bored to a passage way for air through said plug to the bore 8. A rubber tube 12 is connected at one end to the bore 13 in the plug 19, and has its other 50 end connected to a hand operated air bulb of

the usual type. A whistle or bird reed 15 is fitted into the bore 8 of the extension member 4 and is operated by air forced through bore 8 by means of the bulb 15 and elements connected thereto.

The upper part of the member 5 has a cylinder 16 of cardboard or thin sheet material suitably secured thereto. The cylinder 16 extends upwardly in the bore 2 for about one half the length thereof; and this cylinder is enveloped by a rubber envelope or bellows 17 which is likewise suitably secured over the cylinder 16 to the upper end of the member 5. The bellows 17 is somewhat longer than the cylinder 16 and has its upper end turned 65 and seated in a groove 18 formed around the lower end of a solid cylindrical extension 19 of a piston support 20 which projects through the upper end of the cylindrical body 1.

The upper end of the support 20 has secured thereto, or formed integral therewith, a part 21 representing the lower member of the beak of a bird. The tongue 22 of the toy bird is also formed integral with the support 20, or is otherwise suitably secured thereto. 70 The upper end of the piston 20 has its opposite sides cut away to form a flat sided lug 23 transversely bored to receive a pivot pin 24 for pivotally connecting a head member 25 thereto. This member 25 in normal position extends clear across the upper end of the body 1 and over the members 21 and 22 secured to the piston 20. 75

80 The head member 25 is provided with a central groove or depression 26 shaped to receive the projection 23 and to cover the tongue 22 when the head member 25 is in its closed position, indicated by the dotted lines in Figure 3. The head 25 is provided with a bore 27 adapted to receive a cord 28, passing through the said bore and designed to be inserted in a slot 29 formed on the end of a plug 30 suitably secured to the upper part of the head 25.

85 The string 28 extends downwardly 90 through the body 1, past the cylindrical member 5, and through a bore 31 formed at the upper part of the tail end of said body 1. The bore 31 terminates at the end 32 of a slot 33 formed on the lower end of the body 1. 100

The slot 33 is designed to receive the upper end 34 of a tail 35; and a pivot pin 36 passes through the upper end 34 and through the opposite sides of the slot 33 to connect the tail 35 pivotally to the body 1. The cord 28 is then passed through a hole 37 formed in the upper end of the tail 35 and is knotted on the under side of the tail to secure the cord in proper position to said tail.

10 The cord 28 is drawn taut through the body 1 when the tail is in the lowermost position, shown in Figure 2 of the drawings, and is then secured in the notch 29 of the plug 30 with the head member 25 resting against the upper 15 end of the body 1 of the toy. A strip 37' of rubber or other elastic material has one of its ends secured to the lower end of the body 1 and has its other end secured to the under side of the tail 35 so as to hold the tail yielding in its lowest position and, through the 20 cord 28, to hold the head 25 similarly in yielding contact with the upper end 38 of the body 1.

25 The body 1 of the bird is cut away at its lower end in a rough reproduction of the shape of a bird and this cut away part has the legs 39 and 40 suitably secured thereto, the lower ends of the legs 39 and 40 being provided with feet 41 and 42, respectively, to support the bird in position on any horizontal surface.

30 *In operation.*—When the bulb 14 is compressed, air under pressure passes through the bore 13 into the bore 8 and fills the rubber envelope 17, and, striking against the solid end of the extension 19, forces the latter upwardly, as a piston, in the body 1, thereby moving the pivot end of the member 20 to cause the head 25 to swing about the said 35 pivot 24. The cord 28 connecting the head and tail of the toy bird causes the tail to be lifted simultaneously with the raising and swinging of the head member.

35 The lower flat surface 43 of the head member 25 slides along the upper surface 38 of the body 1 as a fulcrum so that the head 25 swings its beak end 44 away from the tongue 45 at the same time as the tail 35 is elevated. During this movement of the head and tail, 40 the air passes through the whistle and reed 15 causing the bird to emit a musical note. The reed 15 forms a restricted passage for the air forced therethrough by operation of the bulb 14, and the emission of this air permits the rubber envelope 17 to collapse, and thereby permit the head 25 to be drawn into its original position by means of the action of the resilient strip 36 on the tail 35.

45 The strip 36 may be omitted whenever the design of the toy bird is such that the parts arranged in the upper part of the body 1 will fall therethrough by gravity, and the tail is of such weight as to assist this fall through the medium of the cord 28 connecting the head and tail to each other.

50 While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

70

75

What I claim is:

1. A toy comprising a cylindrical body, a piston slideable therein, a lug projecting laterally from the one end of said piston and shaped to represent the lower part of a beak, 80 a head pivoted to said piston and including an upper beak part normally in contact with the said lug, and means to pivot said head about said end.

2. A toy comprising a cylindrical body, a piston slideable therein, a lug projecting from one end of said piston and from said body, a head including two parts one of which is fixed to said lug and the other of which is pivoted thereto, and means operated by reciprocating said piston in said body for rotating the pivoted part of said head relative to the fixed part.

3. A toy bird comprising a cylindrical body having a piston reciprocable therein, a tail pivoted to one end of said body, a head having a part fixed to one end of said piston and another part pivoted thereto, and means for simultaneously projecting the piston through one end of said body and swinging the head and tail about their pivotal connections with the piston and body, respectively.

4. A toy bird comprising a cylindrical body, a piston reciprocable in said body, a signal located in said body, a head pivoted to one end of said piston, a tail pivoted to said body, and means connected to said body for simultaneously operating the signal, projecting the piston from one end of said body, and swinging the head and tail about their pivotal connections with the piston and body, respectively.

5. A toy bird comprising a cylindrical body having two axially aligned bores of different diameters formed therein, a stepped cylinder having a part thereof secured in the narrower bore, a bellows having one end fixed to said cylinder, a piston reciprocable in said cylinder and having one end secured to the other end of said bellows, a head pivoted to the other end of said cylinder, and pneumatic means connected to said cylinder to reciprocate said piston therein and simultaneously swing said head about its pivot.

6. A toy bird comprising a cylindrical body having a piston reciprocable therein, a tail pivoted to one end of said body, a head pivoted to said piston at the other end of said body, and means for simultaneously reciprocating said piston on said body and rotating

20 said tail and head in opposite directions about their respective pivots.

25 7. A toy bird comprising a body having a tail pivoted to one end thereof, a head slidably and pivotally connected to the other end of said body, and means for simultaneously sliding said head and rotating said head and tail in opposite directions about their respective pivots.

10 8. A toy bird comprising a body having a tail pivoted to one end thereof; a head slidably and pivotally connected to the other end of said body, a signal located in said body, and pneumatic means for simultaneously 15 operating said signal and sliding said head and rotating said head and tail about their respective pivotal connections with said body.

15 In testimony whereof I affix my signature.
JOHN LARSON.
